CONTROL FOR RECORD SUPPORTING
MEANSGeorge Ramsey, Hampton, Conn., assignor to The
National Cash Register Company, Dayton,
Ohio, a corporation of Maryland

Application February 24, 1941, Serial No. 380,158

6 Claims. (Cl. 197—127)

This invention pertains to record material supporting means of the "front feed" type in which the supporting means normally is in closed-throat position, where it retains the record material in printing position, but is shiftable to an open-throat position, where certain elements of the supporting means are moved to release the record material and form an open throat or guiding passage to permit the ready insertion and removal of said record material into and from the front of the machine. In particular, the invention is concerned with the provision of novel means to control the shifting of the record material supporting means.

In prior art machines employing the "front feed" type of record material supporting means, the shifting of the supporting means to open-throat position required some form of control utilizing the movement of the supporting means to a columnar position or the location of the supporting means in a particular columnar position, or, in lieu of these controls, some manipulative device had to be operated to initiate a throat-opening operation.

All of the prior art requirements and limitations on the control of the throat-opening operations are eliminated in applicant's novel arrangement, in which a source of radiant energy and a detector of such energy are so located in front of the record material supporting means that a beam of radiant energy extends across the machine where the hand of the operator, in moving toward the record material to remove said material, will interrupt the beam, and a circuit in which the detector is included will control an operating means to cause the record material supporting means to move to open-throat position. In the instant embodiment of the invention, the source of radiant energy is a light source, and the detector is a photo-electric cell.

The novel control is particularly useful when used in connection with a record material supporting means supported by a traveling carriage, because it is in no manner dependent upon any carriage movement or position. This condition enables one or more printing operations to be performed in any one or more columns of a record material without causing the supporting means to be shifted to open-throat position, which is not possible when the carriage movement or position is used to control the shifting means. After the desired number of printing operations on the record material, the operator merely reaches for the record material to remove it from the machine, and the supporting means

is shifted to open-throat condition, regardless of the position of the traveling carriage.

Accordingly, it is clear that, when the novel control is used, the operator does not have to make any adjustments of tappets or control elements or operate any keys or manipulative devices; all that is necessary is that the operator perform the natural operation of reaching for the record material, and the throat is opened to release the material so that it may be removed from the machine. The improved control, therefore, simplifies the operation of the machine by the operator, inasmuch as it requires no particular effort on the part of the operator and no special operations of parts or sequence of operations to be remembered by the operator.

It is, therefore, an object of this invention to provide a simplified control for causing a "front feed" type of record material supporting means to be shifted.

Another object of the invention is the provision of a novel control means for shifting a record material supporting means, the operation of said control means requiring a minimum of effort on the part of the person operating the machine.

Another object of the invention is to provide means which are rendered effective to shift a record material supporting means to a released position when the operator reaches for the record material to remove it from the machine.

A further object of the invention is the provision of control means which are rendered effective upon the interruption of a beam of radiant energy to cause a record material supporting means shifting means to operate.

Another object of the invention is the provision of photo-electric control means for controlling the closed- or open-throat position of a "front feed" type of record material supporting means.

A further object of the invention is to provide a beam of light extending across the front of the machine to a photo-electric control means for causing certain elements of a record material supporting means to be moved to a position to permit the removal of record material therefrom when the operator blocks the light from the control means upon reaching for the material.

Another object of this invention is to provide a source of light and a photo-electric cell mounted adjacent a record material supporting means, and an operating means for shifting said record material supporting means, rendered operable under control of said photo-electric cell each time a beam of light from said source of light to said photo-electric cell is interrupted.

Another object of the invention is to provide a control means for use with a "front feed" type of record material supporting means mounted in a traveling carriage for lateral movement therewith, which control means is rendered effective to cause the shifting of the supporting means to an open-throat position in any lateral position of the carriage and at any time, merely by the operator's reaching for the record material.

Another object of the invention is to provide a source of light and a photo-electric cell mounted in such a manner adjacent a "front feed" type record material supporting means carried by a carriage laterally shiftable on a machine, that the hand of an operator of the machine, in reaching for the record material, at any time and in any lateral position of the carriage, will break a beam of light from the light source to the photo-electric cell, which will cause the supporting means to be shifted to an open-throat position to allow the record material to be readily removed therefrom.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

Of said drawings:

Fig. 1 is a side elevation, as observed from the right, showing the shifting mechanism for the record material supporting means and the relative positions of the parts of such mechanism when the supporting means is in closed-throat or printing position.

Fig. 2 is a side elevation, as observed from the right, showing the shifting mechanism for the record material supporting means with the various parts in the positions which they assume when the supporting means is in open-throat position.

GENERAL DESCRIPTION

The "front feed" type of record material supporting means is used where it is desired to insert and remove individual record sheets into and from the front of the machine.

One use of this type of supporting means may be found in a bank where an individual ledger

sheet is provided for each depositor, upon which ledger sheet a record of the daily balancing of his account is printed. Under these circumstances, large numbers of ledger sheets must be inserted into and removed from the machine each day. It is necessary, therefore, that means be provided whereby the ledger sheets may be quickly inserted into the machine, located at the proper printing line, and, after the balancing operation is completed, quickly removed from the machine with the least amount of effort on the part of the operator.

To accomplish this, in the present embodiment, the record material supporting means is shiftable from closed-throat or printing position to open-throat position and vice versa and comprises a platen, pressure rollers, a work table, and guide plates mounted in a frame for shifting movement. When the supporting means is in printing position, the platen is adjacent the printing means, and the pressure rollers engage the ledger sheet with the platen to retain the ledger sheet against movement during a printing operation.

After the printing operation or operations have been completed and it is desired to remove the ledger sheet from the machine, the operator merely reaches for the ledger sheet, and, in so doing, his hand interrupts a beam of light, which causes an operating means to function. The operating means shifts the platen from printing position to a more accessible position and moves the pressure rollers to a position where they, together with the platen, the work table, and the guide plates, form a throat or guide chute to make the removal of the ledger sheet very easy.

A new ledger sheet may then be inserted into the record material supporting means, which can then be shifted manually to printing position, and the operation can be repeated.

It will be clear from the following detailed description that this arrangement requires no setting of control elements or manipulation of control keys, nor does it require any particular effort on the part of the operator to cause the record material supporting means to move to open-throat position.

A journal sheet and superimposed carbon paper are usually used to make a record of the transactions recorded in a plurality of the ledger sheets, and this journal sheet and carbon paper are held on the platen by sets of additional pressure rollers, which are not released by the movement of the record material supporting means to open-throat position. A manually operable member can be operated to release these pressure rollers when it is desired to remove the journal sheet from the machine.

In the instant embodiment, which shows the record material supporting means mounted in a laterally shiftable traveling carriage associated with a well-known form of accounting machine, the source of light and the photo-electric cell are so located that a beam of light extending from the light source to the photo-electric cell can be broken by the hand of the operator in reaching for the record material in any of the positions to which the traveling carriage may be shifted laterally. It is obvious that applicant's novel control means can be used with a record material supporting means which has no lateral shifting movement, since the control is in no way dependent upon any lateral shifting of the supporting means. Furthermore, the record material supporting means is shown asso-

ciated with an accounting machine, but it could equally well be used with any other machine in which a front feed of record material is desired.

DETAILED DESCRIPTION

Accounting machine

The invention is shown as being used with an accounting machine to control the shifting of the "front feed" type of record material supporting means. As the type of accounting machine shown in Fig. 6 is well known and is illustrated and disclosed in the United States Patents No. 2,038,717, which issued to Raymond A. Christian on April 28, 1936, and No. 2,082,098, which issued to Raymond A. Christian on June 1, 1937, only those details of the accounting machine which are necessary to an understanding of the invention will be described herein.

The various mechanisms of the accounting machine are supported by side frames and cross frames, one side frame of which is shown at 81 in Fig. 1. At the front of the machine (Fig. 6) are the usual rows of amount keys 62 and control keys 63.

The machine is enclosed in a cabinet 84 which supports a carriage front guide rail 65 and a carriage rear guide rail 66. A traveling carriage, formed with two connected side members 67 and 68 which carry the various record material supporting means, is laterally shiftable on the guide rails 65 and 66. The lateral shifting of the carriage is used to bring various portions of the record material opposite a set of printing elements 69, from which amounts or other data may be printed.

The manner in which the lateral shifting of the carriage is brought about and the manner of controlling the positioning of the printing type is clearly explained in the above-mentioned Christian Patent No. 2,082,098, to which reference may be had for further details.

Front feed supporting means for record material

The record material supporting means, which enables "front feeding" operations to take place, comprises a platen 70 (Figs. 3 and 4), lower pressure rollers 71, a lower work table 72, and side guides 73 (only one shown). These parts, which are generally similar to those shown in the copending United States application Serial No. 653,838, filed by Raymond A. Christian on January 27, 1933, can occupy a closed-throat position as shown in Fig. 3, where the platen 70 supports the record material in printing position and the pressure rollers 71 hold the material against movement, and also can be shifted to an open-throat position, as shown in Fig. 4, where the platen 70 is raised and the pressure rollers 71 are disengaged from the platen, so that these parts, together with the lower work table 72 and the side guides 73, form a chute or throat in which record material can readily be inserted into or removed from the front of the machine.

The various elements of the record material supporting means are carried by a rockable frame composed of side plates 80 and 81 (Figs. 1, 2, 3, and 4) connected together by tie rods 82 and 83 and a cross bar 84. Secured in the carriage side members 67 and 68 and extending across the carriage is a rod 80, upon which is pivoted a pair of frame-supporting arms for rockably supporting the frame in the carriage. Frame-supporting arm 81 has its rear end bifurcated to engage a stud 82 in the side plate 80

and its forward end 83 hook-shaped to receive a platen-supporting shaft 84, which is journaled in the side plates 80 and 81. In a similar manner, another frame-supporting arm (not shown) is mounted on the rod 80 adjacent the side plate 81 and provides a means for supporting this side of the frame for rocking movement about the rod 80.

The manner in which the various elements of the record material supporting means are mounted in the rockable frame will now be described.

The platen 70 is supported by the shaft 84 rotatably journaled in the side plates 80 and 81 of the rockable frame. The lower sets of pressure rollers 71 (Figs. 3, 4, 7, and 8) are rotatably mounted on studs extending between sets of pressure roller carrying arms 85 loose on a shaft 86 rockable in the side plates 80 and 81.

Stop arms 87 are carried by the shaft 86 and are adjustably connected therewith by means of screws 88 and arms 89 pinned to the shaft. A rod 100 fastened in the arms 87 extends through slots 101 in the pressure roller carrying arms 85 and enables the stop arms 87 to control the position of the pressure rollers 71 as well as their shifted from closed-throat position to open-throat position.

Encompassing the shaft 86 is a series of torsion springs 102 (Fig. 7), one end of each of said springs 102 engaging one of the arms 85 and the other end of each spring engaging a hole in an adjustable collar 103 retained in position on shaft 86 by a set screw. With the set screws loosened, the collars 103 are rotated clockwise about shaft 86, as viewed in Fig. 8, and, through the springs 102, urge the pressure roller carrying arms 85 clockwise, as viewed in Figs. 3, 4, and 8, until the lower part of the slots 101 yieldingly engage the rod 100 with the proper degree of pressure,

after which the set screws are tightened to retain the collars 103 in their set positions. As the collars 103 and the stop arms 87 are both fastened to shaft 86, the pressure caused by the adjustment of the springs 102 will not be affected by the rocking of the shaft 86, and the pressure roller carrying arms 85 will move with the stop arms 87 from closed-throat position as shown in Fig. 3 to open-throat position as shown in Fig. 4, and vice versa.

The lower work table is fastened to the cross bar 84 of the rockable frame, which cross bar also supports the side guides as 73, clamped thereon in any lateral position between the side plates 80 and 81 to control the lateral positioning of the record material. The front edge of the work table 72 is cut away opposite the pressure rollers 71 to allow the pressure rollers to contact the platen in closed-throat position, as shown in Fig. 3. When the lower work table 72 is in open-throat position, its forward edge moves upward to a position adjacent a line finder and guide 104 mounted in brackets 105 and 106 secured to the carriage side members 67 and 68 respectively, and serves to guide the record material toward the rear of the machine.

Frame-rocking mechanism

The mechanism for rocking the frame in which the record material supporting means is carried is substantially the same as that shown and described in the above-mentioned application of Raymond A. Christian, Serial No. 653,838. Only the mechanism located adjacent the side plate 80 of the frame is shown in the drawings, because

it is believed that this is sufficient to enable an understanding to be had of the invention.

Secured in the carriage side member 67 is a stud 107 (Figs. 1 and 2), upon which is pivoted an arm 108 bifurcated to receive a stud 110 secured on an arm 111 fast on a shaft 112 journaled in the side plates 88 and 81 of the rockable frame. Also fast to shaft 112 and adjacent the side plate 81 is an arm 123 (Fig. 8), which has a stud 124 engageable by a bifurcated arm (not shown) similar to arm 108 but pivoted on a stud on the carriage side member 68. These arms, which are pivoted on the carriage side members, have their lower ends connected by a rod 109 (Fig. 1). A spring 125 (Figs. 6 and 8), connected to the arm 123 and to the side plate 81, tends to move the shaft 112 in a clockwise direction as viewed in Figs. 1 and 8. The shaft 112 is prevented from moving clockwise when the frame is in closed-throat position, because a roller 113, carried by the arm 111, engages the end of a link 114 pivoted on stud 115 on the side plate 88. The link 114 is held in the path of the roller 113, as shown in Fig. 1, by a stud 116 on a blocking member 117 loosely pivoted on the shaft 112 but prevented from turning thereon by the engagement of the end 118 of the blocking member 117 with the stud 119 in the carriage side member 67.

In the present embodiment, the frame is rocked by an operating means which engages the rod 109 in any position of the carriage and rocks the arm 108 clockwise about the stud 107. The upper bifurcated end of the arm 108 engaging the stud 110 tries to rock the arm 111 clockwise, but this is blocked by the link 114 being in the path of the stud 115. Since the shaft 112 and the arm 111 are prevented from rotating in the side plates, the movement of the bifurcated end of the arm 108 is transmitted to the side plate 88 through the shaft 112 and also through the link 114 and the stud 115, causing the frame, by means of the frame-supporting arms as 81, to pivot clockwise about the rod 88. The end 118 of the blocking arm 117 has an inner surface 126, which is formed as an arc with the rod 88 as a center, so that, as the frame rocks about the rod 88, the blocking member 117 will continue to hold the link 114 in the path of the stud 115, and this condition will continue until the frame is moved to open-throat position and notch 121 in the member 117 is opposite the stud 119.

When the notch 121 is moved opposite the stud 119, the blocking member 117 is allowed to rotate a slight distance clockwise about shaft 112, and this will allow the link 114 to move from the path of the roller 113 and enable the arm 108 to operate the arm 111 to rock the shaft 112 clockwise in the side plates of the frame. The rocking of the arm 111 with the shaft 112 carries the roller 113 over the upper edge of the link 114 until it rests in the dwell 122. This causes the link 114 to bear on the stud 116 on the blocking member 117 and retain the notch 121 over the stud 118 to lock the frame in open-throat position.

Also fast on the shaft 112 are slotted arms, one of which is shown at 126 in Fig. 8, for rocking the shaft 88 to shift the pressure rollers 71. The operation of these arms 126 is similar, so only one will be described.

In the lower part of arm 126 is a V-shaped slot 127, in which is a roller 128 carried by the arm 129 pinned to shaft 88. In Fig. 8, the arm 126 is shown in open-throat position, to which it has been shifted by the shaft 112 moving clock-

wise. The roller 128 has been shifted from the left-hand end of the slot 127, where it was located until shaft 112 was rocked, to the right-hand end of the slot and has caused the arm 128 to rock the shaft 88 counter-clockwise, as viewed in Fig. 8, and move the arms 87 and the rod 109 to shift the pressure rollers 71 from engagement with the platen 70, or closed-throat position, as shown in Fig. 3, to the open-throat position, as shown in Figs. 4 and 8.

It is thus seen that the frame-rocking mechanism first rocks the frame and moves the platen from printing position to a more accessible position and moves the lower work tray to a position to receive the record material when it is inserted from the front of the machine and thereafter shifts the pressure rollers to release the record material so that it may be readily removed from the front of the machine and a new sheet inserted.

A curved stop member 130 (Figs. 1 and 2) is fastened to the carriage side member 67 and, when the frame is rocked to open-throat position, coacts with a collar 131 carried by the shaft 84 to limit its movement in this direction. A second stop member 132, which is pivoted on the rod 88 and is adjustable vertically by an eccentric 133, engages the collar 131 to arrest the frame in closed-throat position with the platen in proper relation to the printing mechanism. A similar pair of stops, not shown, are carried by the carriage side member 68 and serve to limit the movement of the other side of the rockable frame.

Manual means are provided to rock the frame and the front feed supporting means thereon from open-throat position to closed-throat position. This means is shown in Figs. 1, 2, and 6 and will now be described. Secured on the carriage side member 67 is a bracket 134, to which is pivoted a restoring lever 135 provided with a finger piece 136 and an extension 137. Pivoted to the extension 137 is a link 138 having a slot 139 adapted to cooperate with a stud 140 secured to the arm 111. When the frame is rocked clockwise from closed-throat or printing position to open-throat position, the stud 140 engages the end of the slot 139 in the link 138 and rocks the lever 135 clockwise until the lever engages a bumper 141 carried by the upper stop member 130.

To restore the frame and the front feed record material supporting means to closed-throat or printing position, the finger piece 136 (Figs. 1, 2, and 6) is struck by the operator, and this rocks the lever 135 counter-clockwise, which, through the link 138, the stud 140, and the arm 111, rocks the shaft 112 counter-clockwise to cause the arms as 126 (Fig. 8) to rock the shaft 88 to move the pressure rollers 71 into engagement with the platen 70 and to cause the roller 113 (Figs. 1 and 2) to be removed from locking engagement with the link 114. The release of link 114 allows the notch 121 in the blocking member 117 to leave the stud 119 and enables the frame to move toward closed-throat or printing position. The inertia of the frame and the parts supported thereon will cause the frame to continue to move to closed-throat position even after the restoring lever 135 is returned to normal position and the stud 140 has left the end of the slot 139.

70 Actuating means for the frame-rocking mechanism

The side frames of the accounting machine, one of which is shown schematically at 81 in Fig. 1, support a rockable shaft 142. An arm 143, fas-

tened to the shaft, extends upwardly, so that it can engage the rod 108 in any position of the carriage and can pivot the arms, as 108, clockwise to rock the frame from closed-throat position to open-throat position, as explained above.

The shaft 142 also has fastened thereto an arm 144, which is connected by a link 145 to a source of power shown generally at 146. The source of power may take any convenient form as long as it can operate the link 145 to rock the shaft 142 counter-clockwise when desired. It may comprise a constantly running motor, which can be connected to operate the link 145, or it may consist of a normally inoperative motor, which is connected to the link 145 and can be set in operation each time it is desired to operate the link. It may also take the form of a spring which is latched under tension or compression and which may be utilized to operate the link 145.

Control means for the actuating means

The means for controlling the actuating means for frame-rocking mechanism is most clearly shown in Figs. 6 and 9 and will now be described. In the instant embodiment, a tube 147, carried by the accounting machine cabinet 84, has its upper end bent over, so that it is located adjacent the traveling carriage. At the upper end of the tube 147 is an enlarged section 148 containing a source of radiant energy, which, in the instant embodiment, comprises a light source for directing a beam of light across the front of the machine at a point where the hand of the operator will pass when reaching toward the carriage to remove record material therefrom. Mounted on the machine in the path of the beam of light is another tube 149 containing a photo-electric cell 150 (Figs. 1 and 9), which is included in a circuit carried by a cable 151 to the source of power 146, so that the photo-electric cell can control the operation of the link 145 by the source of power 146.

With the light source carrying section 148 and the tube 149 located as shown in Fig. 1, it is obvious that the hand of the operator in moving toward the record material will block the beam of light from the photo-electric cell and cause the control circuit to function. This circuit, as shown in Fig. 9, may include any desirable form of amplifying means 152 and a control magnet 153, which magnet can be operable, when the beam of light is blocked from the photo-electric cell, to cause the link 145 to be connected to a motor if a constantly running motor is used, or to close a motor switch if a normally inoperative motor is used.

Obvious variations can be made in the control means and the actuating means without departing from the invention. The type of radiant energy used is described as light, but the invention is not to be limited to the use of light, as other forms of radiant energy could be used together with appropriate means for detecting the beam. Inasmuch as the critical location of the source of energy and the detector is such that the beam between them can be broken under proper circumstances, these elements may be used with a record material supporting means that has no lateral travel, or, if a traveling carriage is used, these elements may both be carried by the carriage, or one may be carried by the carriage and one may be stationary, without departing from the purpose of the invention. It is also within the scope of the invention to cause

the control to function by establishing a beam of light instead of interrupting it.

Further, the control means and the actuating means are shown for causing the movement of the frame and the record material supporting means from closed-throat to open-throat position, but it is clear that such a control could readily be utilized to cause the record material supporting means to be moved from open-throat position to closed-throat position.

Additional record material supporting means

Also associated with the platen 70 (Figs. 3, 4, and 5) is a second record material supporting means to guide and hold a second form of record material which is fed from the rear of the machine. The record material is fed from the rear of the machine by operating the knobs 156 (Figs. 1, 2, and 6) to rotate the platen clockwise, and also by the usual line-spacing mechanism (not shown). The second record material supporting means is rockable with the record material supporting frame and comprises sets of upper pressure rollers 157 and lower pressure rollers 158, which cooperate with the platen 70 to hold record material thereon, and an upper work table 159, which, with a guide plate 160 (Figs. 3 and 4) and side guides 161 and 162, guide the record material to the platen from the rear of the machine.

A pair of brackets 163 and 164 are fastened to the side plates 80 and 81, respectively, of the rockable frame, and these brackets have pivoted thereon arms 165 and 166 connected by a rod 167, which carries the sets of upper pressure rollers 157. Springs 168 and 169 are connected to the arms 165 and 166 and to the brackets 163 and 164, respectively, and urge the pressure rollers 157 into engagement with the platen 70. Also pivoted on the brackets 163 and 164 are arms 170 and 171, respectively, which have fastened to their rear ends the upper work table 159 and at their front ends are connected by a spring 172 (Figs. 4 and 5), which rotatably supports the sets of lower pressure rollers 158.

The front edge of the upper work table 159 is cut out opposite the pressure rollers 158. Intermediate the rollers, this edge is curved to embrace the spring 172 and form a support for this spring intermediate the arms 170 and 171. Springs as 173 (only one shown) are fastened to the rear end of the arms 170 and 171 and to the side plates 80 and 81 and urge the pressure rollers 158 into engagement with the platen 70.

The guide plates 160 are carried by the tie rod 83 and the shaft 112 and serve to guide the record material to and from the pressure rollers 157 and 158. The side guides 161 and 162 are adjustably supported on the upper work table 159 and control the lateral positioning of the record material thereon.

This additional record material supporting means is rocked with the frame, but does not release the record material when the frame is rocked. A pair of cams 174 and 175 are fastened on a sleeve 176 rotatable on a shaft carried by the side plates 80 and 81, which cams cooperate with rollers 177, 178, 179, and 180 on the arms 165, 166, 170, and 171, respectively, to separate the forward ends of these arms and move the pressure rollers from engagement with the platen. Counter-clockwise movement of the handle 181 causes the high points on the cams 174 and 175 to move opposite the rollers on the arms and

move the pressure rollers to release the record material.

This additional record material supporting means, which is not released when the frame is moved to open-throat position, can be used to hold a journal sheet and superimposed carbon sheet on said journal sheet in place to record data as it is recorded on a plurality of the ledger sheets which are inserted from the front of the machine in a plurality of operations.

SUMMARY

From the above description it is clear that the improved control means simplifies the operation of the machine, in that it requires no accurate setting of control elements or any special operation of the machine to cause the supporting means to shift to open-throat position. All that is required is that the operator reach for the record material and in so doing interrupt the beam of light to cause the supporting means to be shifted. Since, with any "front feed" type of record supporting means, the operator must remove and insert record material therein, the use of this necessary act without any additional effort on the part of the operator also to cause the throat to open will effect a considerable saving in time and effort if many record sheets are to be handled, as in the case given above, in which daily balances are made on individual ledger sheets.

A copending application of J Willard Welker, Serial No. 380,706, filed on February 28, 1941, shows a photo-electric cell and lamp mounted adjacent a shiftable record material supporting means, as in this application, but the claims of the Welker application are drawn to a novel form of actuating means which is not shown in the instant application.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In a device of the class described, the combination of means for supporting record material; means to shift said supporting means from a closed-throat position, where the supporting means holds the record material in working position, to an open-throat position, where the supporting means releases the record material for removal therefrom, and vice versa; means for producing a beam of radiant energy; means to detect said beam of radiant energy; means to direct said beam of radiant energy across the normal path of the hand of the operator when reaching for said record material whereby the operator's hand will block said beam when the operator reaches for said record material; actuating means for said shifting means; and means controlled by said detecting means for causing the actuating means to be operative to actuate the shifting means when the beam of radiant energy is blocked from said detecting means by the hand of the operator reaching toward the supporting means.

2. In a recording machine, the combination of a record material supporting means for receiving record material fed thereto from the front of the machine and including a platen and cooperating pressure rollers shiftable from a closed-

throat position to an open-throat position and vice versa; means for producing and directing a beam of light across the record material supporting means and in front thereof; a photo-electric cell upon which said beam of light is directed; means for shifting said record material supporting means to open-throat position; normally inoperative actuating means for said shifting means; control means for rendering said actuating means operative; and a circuit connecting the photo-electric cell and the control means so that the photo-electric cell can cause the control means to render the actuating means operative each time the beam of light in front of the supporting means is blocked from the photo-electric cell, whereby the operator of the machine in performing the natural operation of reaching for the record material to remove it from the machine can, without any further effort, block the beam of light and cause the supporting means to be shifted regardless of whether or not the recording machine has been operated one or more times.

3. In a recording machine operable to make records on material inserted into and removed from the front of the machine, the combination of record material supporting means comprising elements shiftable from a closed-throat position to an open-throat position and vice versa; means mounted adjacent one end of said supporting means for producing a beam of light across and in front of the supporting means; a photo-electric cell mounted adjacent the other end of the supporting means and in the path of said beam of light; means for shifting said supporting means to open-throat position; actuating means for said shifting means; and means controlled by said photo-electric cell for controlling the actuating means to shift the supporting means whenever the beam of light is blocked from said cell even though the recording machine has or has not been operated one or more times.

4. In a recording machine, the combination of a record material supporting means for receiving record material inserted therein and removed therefrom from the front of the machine and comprising record material engaging elements shiftable out of engagement with each other to form an open throat; a laterally shiftable carriage for carrying said supporting means; means located adjacent one end of the carriage and operable to produce a beam of light extending in front of the supporting means at any point in the lateral shifting of the carriage; a photo-electric cell located adjacent the other end of the carriage and having said beam focused thereon; means for shifting said supporting means to open-throat position; normally inoperative actuating means for said shifting means; control means for rendering the actuating means operative; and a circuit containing said photo-electric cell and said control means for enabling said photo-electric cell to render the control means effective in any position of the carriage and at any time in the operation of the machine whenever the beam of light in front of the supporting means is blocked from the photo-electric cell as the operator reaches to remove the record material from the machine.

5. A front feed machine of the class described having front feed means including a platen for receiving and holding a work sheet in front feed position relative to said platen; said front feed means being movable from a closed to open throat position and vice versa; a photoelectric

cell; light producing means to produce a beam of light; means to direct said beam of light to cause the same to fall upon said photoelectric cell and across the normal path of the hand of the operator when reaching for a work sheet on said platen whereby the operator's hand will interrupt the said beam and prevent the same from contacting said photoelectric cell when the operator reaches for said work sheet; and means rendered operative by said photoelectric cell for moving said front feed means from a closed to an open throat position upon interruption of said beam of light.

6. In a recording machine operable to make records on record material inserted into and removed from the front of the machine, the combination of record material supporting means including elements movable from a record material retaining condition to a record material releasing condition and vice versa; means mounted adjacent one end of said supporting means

for producing a beam of radiant energy across and in front of the supporting means; detecting means mounted adjacent the other end of the supporting means and upon which said beam of radiant energy is directed; means for moving the movable elements of the supporting means to record material releasing condition; driving means operable independently of the recording machine to actuate the moving means; and means controlled by the detecting means for controlling the operation of the driving means to cause the movable elements to be moved to record material releasing condition whenever the beam of radiant energy is blocked from the detecting means, said driving means, when controlled, being operable to cause the movable elements to be moved to record material releasing condition as often as desired regardless of whether or not the recording machine has been operated.

GEORGE RAMSEY.
